CLAIM

The ornamental design for a trolley for bag, as shown and described.

DESCRIPTION

FIG. 1 is a front, left, and top perspective view of a trolley for bag, showing my new design;

FIG. 2 is a rear, right, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is another front perspective view thereof, showing environment;

FIG. 10 is another rear perspective view thereof, showing environment; and,

FIG. 11 is another left side perspective view thereof, showing environment.

The broken lines depict portions of the trolley for bag that form no part of the claimed design. The additional broken lines in FIGS. 9, 10, and 11 showing a bag depict environmental subject matter that forms no part of the claimed design.

1 Claim, 11 Drawing Sheets
